CLAIM

The ornamental design for an iris recognition device, as shown and described.

DESCRIPTION

FIG. 1 is a front and right perspective view of an iris recognition device;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view of the top portion thereof with the bottom portion removed.

In the drawings, the broken lines depict portions of the iris recognition system that form no part of the claimed design.

1 Claim, 7 Drawing Sheets
